TOWED GLIDER WITH AUTOMATIC TOW CABLE RELEASE

Russell M. Carlson, Milford, Conn., assignor to United Aircraft Corporation, East Hartford, Conn., a corporation of Delaware

Application March 6, 1947, Serial No. 732,805

12 Claims. (Cl. 244—3)

1

This invention relates to towed gliders and has as one of its objects the provision of mechanism for automatically releasing the towing bridle of a towed glider upon ground contact following flight.

Another object of the invention is the provision of mechanism of this type which will enable the glider to be towed by the bridle during take-off and which will automatically reset itself following take-off to release the towing bridle upon ground contact following flight.

A further object of the invention is the provision of tow release mechanism operated by a ground contacting member and having air speed responsive means for conditioning the mechanism during flight for automatic release by said member upon landing.

A further object of the invention is generally to improve the construction and performance of towed gliders.

These and other objects and advantages of the invention will become apparent from the appended claims and from the following detailed description of the accompanying drawings which illustrate one embodiment of the invention.

In these drawings:

Fig. 1 is a perspective view of a towed glider embodying the invention shown in flight;

Fig. 2 is a perspective view on an enlarged scale, with parts broken away, of a part of the automatic release mechanism;

Fig. 3 is a sectional view through this mechanism showing the parts in the position which they occupy when the glider is on the ground ready for take-off;

Fig. 4 is a similar view showing the parts in the position they occupy when the glider is in flight with the mechanism reset for automatic release upon ground contact and indicating in broken lines the position of the parts upon automatic release of the bridle;

Fig. 5 is a section on line 5—5 of Fig. 3;

Fig. 6 is a section through an outboard fitting on a bridle post showing the releasable connection for one end of the bridle; and

Fig. 7 is a modification showing an off-set tow apparatus.

As herein shown the towed glider, generally indicated in Fig. 1 by the numeral 10, comprises a long cylindrical fuselage 12 supporting two wings 14 and 16 located substantially mid-way between the fore and aft ends of the fuselage, two tail surfaces 18 and 20 located at the extreme aft end of the fuselage, tow bar assemblies 22, 24 located at the extreme forward end of the fuselage, and suitable alighting gear.

2

The alighting gear comprises two main wheels 26 and 28 mounted on laterally extended cantilever leaf springs 30 and 32 just aft of the main wings 14, 16 and a nose skid 34 carried by a hollow nose section 36 of the fuselage. Nose section 36 also supports the tow bar assemblies 22, 24 each of which comprises identical, tubular bridle posts, or tow bars, 38 of streamlined cross section, the outboard ends of which receive the shanks of fittings 40 and the inboard ends of which have fittings 42 rigidly secured in a solid nose portion 44 of section 36. The fittings 40 are of streamlined cross section extending fore and aft thereof and are supported by tension cables 46 extending inboard and aft therefrom to the fuselage nose section 36 for the purpose of supporting the bridle posts against bending moments caused by a tow cable 48 which is connected to the glider by means of a V-bridle 50, the divergent aft ends of which are secured to flat plates 52 which are received in slots, or kerfs, 54 extending fore and aft in the end fittings 40. Each plate 52 is provided with a circular aperture 56 adjacent its aft end which registers with a transverse passage 58 in its fitting 40 in which a latch pin 60 is reciprocable between a plate released position in which it is withdrawn from the aperture 56 in plate 52 and a plate locking position in which it passes through this aperture.

The pins 60 are normally biased to locking position in which they enter into apertures 56 and releasably hold the ends of the bridle 50 attached to the fittings 40. To this end the inboard end of each passage 58 in the shanks of fittings 40 is provided with an enlarged portion 62 to receive a compression spring 64 surrounding the pin 60 therein. The spring acts at one of its ends against a transverse pin 66 fixed in pin 60 and at its other end against a closure plate 68 for the inboard end of the enlarged portion 62. Plates 68 have holes 70 therein through which pins 60 extend, and the inboard ends of pins 60 are fixed to cables 72 which extend inboard through tubular bars 38 into the hollow nose section 36, a short length of the cables 72 being exposed at the base of bridle posts 38 as is shown most clearly in Fig. 2.

The cables 72 from the two latch pins 60 at the ends of bridle posts 38 are identical and symmetrical with respect to the nose section 36 and are attached at their inboard ends to the opposite forward corners of a rigid, generally rectangular frame 14 pivoted intermediate its ends on a transverse bolt 76 which extends through the opposite side walls of the nose section 36, as shown most clearly in Figs. 2 and 5. The aft end of

frame 74 has a latch plate 77 pivotally mounted intermediate its ends between the sides of frame 74 on a pin 78 and is constantly biased by a pair of torsion springs 80 in a clockwise direction, as viewed in Fig. 2, so that one end of the latch plate normally rests against the aft end member 82 of frame 74 while its other end projects forward and downward below frame 74 for a purpose herein-after described.

The nose skid 34 is pivotally supported at its forward end on a pin 84 mounted in a rigid bracket 86 formed integral with the solid nose portion 44 of nose section 36. At its aft end the skid is supported by a shock absorbing oleo strut including an upper cylinder element 88 having an end fitting 90 and a cooperating lower piston element 92 having an end fitting 94. A pivot pin 96 carried by a pair of upstanding ears 98 on skid 34 extends through fitting 94 to pivotally connect piston element 92 with the skid. The oleo strut extends freely upward through an ample opening 100 in the bottom of nose section 36 and has its upper end fitting 90 pivotally mounted on a pin 102 which extends between the upper ends of two parallel links 104, the lower ends of which are pivotally supported between the sides of frame 74 on bolt 76. A suitable tubular spacer 106 is provided on the bolt 76 between the lower ends of links 104, and shorter but similar spacers 108 are provided between the upper end of each of these links and fitting 90 of oleo cylinder element 88.

At one of its ends a compression spring 110 abuts the lower extremity of cylinder element 88 and at its other end abuts pin 96 to constantly bias the elements 88 and 92 of the oleo strut into the fully extended position thereof shown in Fig. 4, in which the parts are shown in the position they occupy just prior to landing. An outstanding lug 112 fixed to the upper end of cylinder element 88 and projecting aft of the latter has a flat upper face 114 adapted to engage the lower end of the latch plate 77 when the skid and attached oleo strut are in their lowermost position as illustrated in this figure, into which position they are biased by gravity when the airplane is off the ground. With the parts in the position shown in Fig. 4 it will be evident that engagement of skid 34 with the ground in landing will result in the rotation of frame 74 counterclockwise, as indicated by the arrow in this figure, and the withdrawal of locking pins 60 to release the plates 52 at the ends of the bridle 50.

The oleo will continue its upward movement into the position shown in Fig. 3 in which it is held releasably by a latch 116 carried by a spring loaded drag flap 118 pivotally supported at 120 on nose section 36. Flap 118 is biased by a torsion spring 122 into the elevated position shown in Fig. 3, the strength of the springs being designed to maintain the flap elevated until a predetermined airspeed has been attained in flight, the spring 122 permitting the flap to move downward as the fitting 90 on the upper end of the oleo in moving upward engages the latch 116 and moves back of the latter into engagement with a stop 124.

When in flight the selected airspeed has been reached which may be, for example, 150 miles an hour, the flap will be deflected downwardly against the action of spring 122 sufficiently to move latch 116 out of holding engagement with fitting 90 of the oleo strut and permit the latter to move by gravity into the Fig. 4 position in which the lug 112 is beneath latch plate 77 and

the automatic release mechanism for the tow bridle 50 is reset.

In the position of the skid and its attached oleo strut when the airplane is on the ground, as shown in Fig. 3, the cylinder element 88 of the oleo strut is fixed, its fitting 90 being held against stop 124 on nose section 36 by latch 116 with lug 112 well above the latch plate 77 so that the piston element of the strut is free to move into and out of cylinder 88 to absorb the landing energy in compression spring 110 and the oleo strut in a usual manner.

In operation, prior to making a flight the spring loaded latch pins 60 will be withdrawn from the kerfs 54 in fittings 40 by pulling the cables 72 where the latter are exposed near the base of the tow bars 38. This enables the plates 52 on the ends of the bridle 50 to be inserted into the fittings 40 and releasably engaged by pins 60.

As the glider stands on the ground prior to take-off the oleo strut occupies the position shown in Fig. 3 in which its fitting 90 engages the stop 124 and the lug 112 carried by cylinder 88 is a substantial distance above latch 77 on frame 74. The flap 118 under these conditions is biased by its spring 122 into the elevated position of the flap shown in Fig. 3 in which the latch 116 forming a part thereof abuts the fitting 90 and prevents the latter from moving away from stop 124. The parts will remain in the Fig. 3 position during take-off and initial flight until the airspeed is sufficient to overcome the force of spring 122 and depress the flap 118 a sufficient amount to release the oleo strut from the holding engagement of latch 116. During take-off the oleo strut is free to operate in its usual manner to absorb shocks in the event that the glider bounces but the cylinder element 88 thereof which carries the abutment 112 will remain stationary relative to frame 74 and hence the bridle release mechanism cannot operate. When released the oleo strut and the skid 34 will drop by gravity into the Fig. 4 position in which lug 112 is beneath the latch plate 77, thus resetting the automatic bridle release mechanism.

Upon landing, the initial engagement of nose skid 34 with the ground will result in movement of frame 74 in a counterclockwise direction about its pivot 76, viewed in Fig. 4, as cylinder 88 of the oleo strut which carries lug 112 moves upward. As frame 74 reaches the broken line position shown in Fig. 4, the cables 72 will have been withdrawn sufficiently in passages 58 to free the plates 52 on the ends of the tow bridle 50, thus releasing the glider from the towing plane. As the oleo strut continues its upward movement surface 114 of lug 112 moves away from latch plate 77 allowing the frame 74 to resume its normal horizontal position, this movement being effected by the force of springs 64 which acting through cables 72 bias the frame constantly into the normal position thereof shown in Fig. 3 and in full lines in Fig. 4. As fitting 90 approaches stop 124 it engages latch 116 and depresses the flap 118 sufficiently to allow the fitting to move behind this latch into the position shown in Fig. 3 in which the glider is ready for another flight.

In Fig. 7 a somewhat modified tow apparatus has been shown which permits off-set towing of the glider. In this modification the plates 52 instead of being attached directly to the ends of the V-bridle are provided with pulleys 126 over which the ends 128 of tow-bridle 130 run. The ends of the tow bridle are connected by a transverse chain 132 which runs over a driving sprocket

134 mounted in the nose portion 44 on the splined end 136 of the shaft 138. It will be evident that rotation of shaft 138 in flight will shorten one end of the bridle 130 while lengthening the other. Simultaneously with the rotation of shaft 138, control surfaces 140 on the bridle posts 38 are differentially operated in such manner as to produce a side force the resultant of which lies along the axis about which the V-bridge 130 rotates and the magnitude of which exactly balances the side forces induced by the bridle so as to cause the glider to fly in an off-set position relative to the towing airplane. The sprocket 134 is loosely received on the splined end 136 of shaft 138 so that a forward movement of the chain 132 will cause the sprocket to be pulled off the shaft. The cable ends 128 and chain 132 run in tubular casings 142 one of which is in front of each bridle post 38 and is secured to the post by means of a pair of clips 144 and 146.

It will be evident that upon release of the plates 52 as described in connection with the construction of Figs. 1-6 the casings 142 will be pulled out of clips 144, 146 and the pulley 134 will be pulled off the splined end 136 of the drive shaft 138, thus releasing the glider from the bridle 130. During this releasing operation the bridle 130 will occupy a symmetrical position relative to the glider, automatic mechanism (not shown) being provided for controlling the rotation of the shaft 138 in response to movement of flap 118 so that upon a reduction of airspeed affecting this flap the glider will be restored to an in-line position with the towing plane. This off-set towing mechanism is shown in detail and claimed in Patent No. 2,507,957 and reference is made thereto for a more complete understanding of this mechanism.

It will be evident that as a result of this invention, mechanism has been provided which enables a glider to be towed during take-off and which automatically resets itself following take-off to enable the towing bridle to be released upon ground contact following flight.

It will be further evident that an automatic tow release mechanism has been provided which is operated by a ground contacting member and which has airspeed responsive means for resetting the mechanism during flight. While two embodiments of the automatic tow release mechanism of this invention have been disclosed for purposes of illustration, it will be evident that various changes in the construction and arrangement of the parts may be made without departing from the invention as defined by the following claims.

I claim:

1. A glider adapted to be towed by a powered airplane including, a ground engaging member, a tow bridle having a releasable connection to said glider, means for releasing said connection upon ground engagement of said member, means for disabling said releasing means during take-off, and airspeed responsive means including a flap pivoted to said glider and projecting into the airstream operative during flight for disabling said disabling means.

2. A glider adapted to be towed by a powered airplane including, a tow bridle, means for releasably connecting said bridle to said glider, mechanism for operating said releasing means including a ground engaging member on said glider, means conditioned when said glider is on the ground including a latch for holding said mechanism in an inoperative position, and airspeed responsive means including a flap pivoted to said glider and projecting into the airstream for mov-

ing said latch out of holding position to reset said mechanism to its operative position during flight.

3. A glider adapted to be towed by a powered airplane including, a tow bridle, mechanism for releasably connecting said bridle to said glider, landing gear including a ground engaging member and an oleo strut connected at its opposite ends to said member and glider, said strut having a lost motion connection with said glider, a stop against which the glider connected end of said strut abuts, mechanism for releasing said tow bridle connection having an operative connection with said strut in the fully extended position of said landing gear, means for latching said landing gear with said strut engaging said stop, and airspeed responsive means controlling the release of said latching means during flight for releasing said landing gear and resetting said releasing mechanism.

4. A glider adapted to be towed by a powered airplane including, a ground engaging member having a lost motion connection with said glider whereby said member occupies one position relative to said glider when the latter is on the ground and a second position when the glider is airborne, a tow bridle having a releasable connection to said glider, means for automatically releasing said releasable connection as said member moves from said second position into said one position upon ground engagement of said member in landing, and airspeed responsive means including a flap pivotally supported on said glider and adapted to have the major portion of its surface project into the airstream for latching said member in said one position during take-off and for releasing the same for movement to said other position to reset said releasing means following take-off.

5. A glider adapted to be towed by a powered airplane including, a tow bridle, means for releasably connecting said bridle to said glider, landing gear including a ground engaging member and an oleo strut connecting said member with said glider, said strut and member adapted to occupy an upper position when said member is in contact with the ground and a lower position when said glider is in flight, latch means operatively connecting said strut with said releasing mechanism for releasing said bridle upon upward movement of said strut as a result of ground engagement of said member in landing, a latch for holding said landing gear in its upper position, and airspeed responsive means for releasing said latch and returning said landing gear to its lower position during flight.

6. A glider adapted to be towed by a powered airplane including, a fuselage, main sustaining surfaces projecting laterally from said fuselage intermediate the ends thereof, bridle posts projecting laterally adjacent the forward end of said fuselage, a V-bridge having the ends thereof releasably connected to said bridle posts, means for releasing said bridle ends including a pivoted member, a nose skid pivoted to said fuselage adjacent the forward end thereof, an oleo strut having its lower end pivoted to said skid, link means having one end pivoted to said fuselage and the other end pivoted to the upper end of said strut, a stop for arresting the upward movement of said strut, a latch for holding said strut in its upper position against said stop, and an airspeed responsive member for moving said latch out of strut holding position during flight, and cooperating means carried by said strut and said pivoted

member for pivoting the latter as said strut moves upward upon engagement of said ground engaging member during landing.

7. A glider adapted to be towed by a powered airplane including, a tow bridle, mechanism for releasably connecting said bridle to said glider, landing gear including a ground engaging member and an oleo strut connected at its opposite ends to said member and said glider, said strut having a lost motion connection with said glider, a stop against which said glider connected end of said strut abuts when said member is on the ground, means for latching said landing gear with said oleo strut engaging said stop, airspeed responsive means controlling said latching means, and means operated by ground engagement of said member in landing for releasing said connecting mechanism as said oleo strut moves through said lost motion into engagement with said stop.

8. A glider adapted to be towed by a powered airplane including, a fuselage having a nose portion, main sustaining surfaces extended laterally from said fuselage intermediate the ends thereof, bridle posts extended laterally from said nose section, a V-bridle having its divergent ends releasably connected to said posts, mechanism including a pivoted member mounted in said nose section for effecting release of said bridle connections, a nose skid having its forward end pivotally connected to said nose section, an oleo strut pivotally connected to said skid adjacent the aft end of the latter, a lost motion connection between said strut and glider including link means having one end pivotally connected with said nose section and the other end pivotally connected with the upper end of said oleo strut, abutment means for limiting the upward movement of said oleo strut, a latch for holding said strut and skid in position in which said strut engages said abutment, a drag flap responsive to a predetermined airspeed for moving said latch out of holding engagement whereby said strut is free to extend, cooperating latch and abutment means, and one supported on said strut and the other on said pivoted member for effecting movement of the latter to release said bridle upon upward movement of said strut due to ground engagement of said skid.

9. In a glider adapted to be towed by a powered airplane including, a fuselage having a nose section, a V-bridle, bridle posts extended laterally from said nose section having latch means at their extremities providing releasable connections for the divergent ends of said bridle, means controlling the release of said connections including a pivoted element, a ground engaging member, a strut connecting said member to the glider having an operative connection with said pivoted element, means for releasing said latch connections upon ground engagement of said member in landing, and abutment means engaging said strut for disabling said releasing means during take-off.

10. A glider adapted to be towed by a powered airplane including, a fuselage, bridle posts extended laterally from said fuselage, latch means at the extremities of said posts, latch engaging

members releasably connected to said posts by said latch means, each having a pulley mounted thereon, a V-bridle having its divergent ends passing over said pulleys, means for connecting said bridle ends, means carried by said fuselage for laterally displacing said connecting means to off-set said bridle, a ground engaging member, and means operative upon ground engagement of said member following flight for actuating said latch means to release said latch engaging members.

11. A glider adapted to be towed by a powered airplane including, a fuselage, bridle posts extended on opposite sides of said fuselage, tubular members disposed in front of said posts, means frictionally connecting said members to said posts, latch means at the extremities of said posts, latch engaging members releasably connected to said posts by said latch means, each having a pulley mounted thereon, a V-bridle having its divergent ends passing over said pulleys and extending into said tubular members, a drive shaft mounted in said fuselage having its end projecting into the plane of said tubular members, a sprocket loosely splined to the end of said shaft, a chain running over said sprocket and connected to the ends of said bridle within said tubular members, means for driving said shaft to off-set said bridle, a ground engaging member, and means operative upon ground engagement of said ground engaging member following flight for actuating said latch means to release said latch engaging members.

12. In a glider adapted to be towed by a powered airplane including, a fuselage having a nose section, bridle posts extended laterally from said nose section having latch means at their extremities, latch engaging members releasably connected to the ends of said posts by said latch means, each having a pulley, a V-bridle having its divergent ends passing over said pulleys, a chain between said pulleys connecting said bridle ends, a fore and aft extended shaft having a driving end projecting forward of said nose section, a sprocket loosely carried by said shaft and operatively engaging said chain, a ground engaging member, and means operated upon ground engagement of said member for releasing said bridle including a pivoted member having operative connections with said member and said latch means.
